UNITED STATES PATENT OFFICE.

ALBERT GOTTLIEB, OF NEW YORK, N. Y., ASSIGNOR TO PACIFIC NOVELTY COMPANY, OF NEW YORK, N. Y., A CORPORATION OF NEW YORK.

DISPLAY DEVICE.

Application filed May 16, 1924. Serial No. 713,653.

To all whom it may concern:

Be it known that I, ALBERT GOTTLIEB, a citizen of the United States, and a resident of the city of New York, county of Bronx, 5 State of New York, have invented a new and useful Improvement in Display Devices, of which the following is a specification.

This invention relates to a device for displaying small articles such as children's rattles, small toys or any similar articles which can be readily suspended from the device and exhibited in such suspended position, and has for its object to provide an article of this character which will be strong and 15 sturdy in construction, which can be readily dismantled for shipment and which will hold the articles displayed by it in such a manner that they can be readily removed, although they are prevented from being inadvertently dislodged or displaced from 20 their positions of display.

With these objects and such other objects as may hereinafter appear, in view, I have devised the particular arrangement herein- 25 after set forth and more particularly pointed out in the claim appended hereto.

Reference is to be had to the accompanying drawing forming a part hereof, in which

Figure 1 is a perspective view of my im- 30 proved display device, and

Figure 2 is a sectional view on the line 2—2 of Figure 1, looking in the direction of the arrows.

In the embodiment of my invention dis- 35 closed in the accompanying drawing, 1 indicates the base of my improved display device which consists of a circular member having a central boss 2 which is provided with a threaded aperture which receives the 40 lower threaded end 3 of an upright supporting member 4. This member 4 may be of any suitable height and is in the form of a rod which receives on its upper end a hub 5 of the support which receives and holds the 45 articles to be displayed. The upper end of the rod 4 loosely fits the interior of the hub 5 so that said hub and the parts carried by it can freely rotate independently of the upright support 4.

Extending radially from the hub 5 is a

plurality of braces or flat supports 6 and secured to the ends 8 of each of said supports is an arcuate bar or rod 7 which forms a support for articles 13 to be displayed. The articles 13 disclosed in the drawing are shown as rattles although it will be understood that any articles which may be hung in a suspended position from the supporting member 7 may be readily displayed on the device. 55

The ends of the supporting member 7 are bent upwardly and these upwardly projecting portions, which are shown at 9 hold the articles 13 on the member 7 preventing the articles from being displaced or inadvertently dislodged from their positions on their supports 7. 60

The upper end of the hub 4 terminates in a ball-shaped projection 10 and extending upward therefrom is a spring clip 11 which 70 is utilized to receive and hold a display card 12 bearing suitable advertising matter or the price of the articles displayed on the device.

It will be seen that the various arcuate supporting members 7 co-operate to form a 75 substantially circular "ring" around the ends of the braces 6 and when a plurality of articles are displayed upon said supports 7, a very pleasing display effect is produced.

From the foregoing it is obvious that my 80 invention is not to be restricted to the exact embodiment shown, but is broad enough to cover all structures coming within the scope of the annexed claim.

What I claim is: 85

An article of the class described comprising a base, an upright projecting therefrom, a hub rotatively mounted on the upper end of said upright, a plurality of braces extending radially from said hub, an arcuate sup- 90 porting rod secured to the end of each of said braces and adapted to receive and hold articles fitted over it, said supporting rods being spaced apart from one another and each of said rods having a pair of upturned 95 ends for preventing accidental removal of the articles supported on said rods.

Signed at the city, county, and State of New York, this 14th day of May, 1924.

ALBERT GOTTLIEB.
